L. D. BRAINERD,
ELECTRIC LANTERN,
APPLICATION FILED DEC. 31, 1919.

Patented May 31, 1921.

FIG. 1.

FIG. 3.

FIG. 2.

Leigh D. Brainerd
By Chester W. Brown
His Atty.

UNITED STATES PATENT OFFICE.

LEIGH D. BRAINERD, OF CHICAGO, ILLINOIS.

ELECTRIC LANTERN.

1,380,091.

Specification of Letters Patent. Patented May 31, 1921.

Application filed December 31, 1919. Serial No. 348,707.

To all whom it may concern:

Be it known that I, LEIGH D. BRAINERD, a citizen of the United States, residing in the city of Chicago, in the county of Cook and

5 State of Illinois, have invented certain new and useful Improvements in Electric Lanterns, of which the following is a specification.

My invention relates to that class of electric lanterns in which one or more incandescent electric light bulbs are connected in circuit with one or more batteries, which cause the bulbs to glow whenever the current from the batteries is passed through the

15 bulbs.

One object of my said invention, is to provide a lantern of this class which will be simple in construction and operation, low in cost, and durable in use.

20 Another object is to provide a lantern of this class which may be used interchangeably in printing and developing films, prints, or negatives in the photographic dark room, or for general illumination in

25 the house or out of doors.

Another object is to provide a lantern of the class described, in which the color of the light may be easily and quickly changed from red, ruby, orange or other color to

30 clear and the reverse, as desired in use.

Another object is to provide a lantern of this class in which the current will be broken automatically whenever the lantern is placed at rest out of use, and one in

35 which by means of double reflectors the light is reflected both forward and downward toward the table, floor or ground, and away from the eyes of the operator.

Other objects of my said invention are

40 more particularly set forth in the accompanying specification, and will be apparent from the following description and accom-

panying drawings:

In the accompanying drawings, in which

45 like numerals of reference refer to similar

parts throughout the various views,

Figure 1 is a side elevation of my said invention, with portions of the outer casing broken away to show interior parts.

50 Fig. 2 is a top plan view, with portions of the cover broken away to show the parts within.

Fig. 3 is a detail view of the glass interchangeable opening, and the slideway for

55 insertion and retention of said glass.

Referring now more particularly to the

accompanying drawings, the numeral 1 designates the case or container which I employ to house my battery and light bulb. This case is substantially rectangular in 60 cross section, and may be made of sheet metal or other suitable material, and of a size suited to contain one or more of the commercial dry cell batteries now offered for sale on the market. At the upper front 65 side of said case, I have provided an inclosed chamber 2, within which I have placed the electric light bulb 3. The upper wall of said chamber 4 is preferably polished to form a reflector, and the rearward 70 wall 5 of said chamber is also preferably polished to form a reflector. At the front of said chamber I have provided a glass plate, as 6 mounted to slide in grooves in the case as at 21 and 22 Fig. 3, to provide 75 ready and convenient means to remove said glass and insert others in its place when desired, to change the color of the light from said lantern.

For convenience in inserting and supporting the electric light bulb 3, I have provided a suitable socket 7, mounted in the rear wall of the chamber as shown, with its screw socket in electric conducting contact with said wall 5 for a purpose hereinafter 80 explained.

Within my case 1 I have placed the dry cell battery 8, which may be of any usual style, and which has the terminal 9 at its central portion, and the terminal 10 at 90 its periphery, as is customary in such batteries. Mounted upon the central terminal 9 of said battery, I have employed the L shaped member or bracket 20, which has a slot at one end suitable for straddling the 95 screw of the contact terminal 8, and is held against displacement by the binding nut 11 usually employed upon battery terminals. At the end of said bracket toward the light chamber, I have provided the screw 12 passing through said bracket, and held in position by the nut 13. This screw 12 is disposed in line with the central terminal of the electric light bulb 3, and is adjusted to contact with said central terminal whenever the bulb is screwed into the socket 7, and is designed to form an electric circuit between the said central terminal of the light bulb, and the battery, through the screw 12, the bracket 20 and the battery terminal 9. 105

On the side of the case adjacent the second terminal of the battery 10, I have mount-

ed the spring contact arm 23, with its free end 14 bent inward at a right angle, and passing through an opening 15 in the wall of said case 1, in proximity to the battery terminal 10. This spring contact arm is held normally out of contact with the battery terminal 10, until forced inward into contact therewith either by the hand of the operator, or by the handle as hereinafter described. When said spring contact arm is so forced into contact with said battery terminal 10, it completes the electric circuit through the battery and the light bulb, by means of the spring contact arm, and the wall of the case 1, and the wall 5 of the light chamber, the lamp socket, and the terminal of the light bulb connected to the screw stem of said bulb.

For convenience in carrying and operating said lantern, I have provided a handle 16, pivoted on opposite sides of said case 1 as at 19—19. This handle is so positioned with reference to the spring contact arm 23, that whenever the handle is raised as in the position shown in the dotted lines, it will contact with said arm, and force it inward into contact with the battery terminal 10, thereby completing the electric circuit, and causing the light bulb to glow. Whenever it is desired to extinguish said light, the handle is lowered out of contact with said spring 23, and the spring 23 returns to its normal position out of engagement with the battery terminal 10, breaking the electric circuit.

I have made the cover 17, with the edge 18 turned downward, to provide a light-tight joint when the cover is placed in position on the top of the case, and at the same time it is easily removable to change the glass, or battery, or to inspect the parts within said case whenever required.

In operation, a suitable battery is inserted in the case and the central binding post 25 connected with the bracket 20. A suitable electric light bulb is screwed into the socket in the light chamber, and the lantern is ready for use. For dark room photographic development, a red, ruby or orange colored glass may be inserted in the front, and the lantern will throw the light downward upon the negative or film being developed. When it is desired to expose a print or film or lantern slide in printing, the glass may be removed, and the light used for the purpose of the exposure, and when the exposure is completed, the glass may be replaced, and the same lantern employed during its development.

For house use, the lantern may be carried by the handle, placed upon the table, stand, or other support, or may be suspended by the handle. In outdoor use, the lantern is usually carried by the handle, or may be carried in the hand. It will be seen that by my special construction, the light is always reflected forward and downward, and the roof, or cover of the lantern shades the light, so that it is never reflected in the eyes of the operator. By this special construction, I secure the full illumination of the objects desired, without the disadvantage of blinding the operator by the direct light from the lantern.

Having thus described my said invention, what I claim and desire to secure by Letters Patent, is the following:

1. In a device of the class described, the combination of a casing having an inclosed light chamber with upper and rear reflectors and glass front opening, an electric light bulb mounted in said light chamber, one terminal in electric contact with the rear reflector, a removable battery within said casing, the central terminal connected with the remaining terminal of the bulb, a spring contact shoe mounted on the casing for contacting with the second terminal of the battery, a cover with downward projecting edges for inclosing the said casing, all substantially as shown and described.

2. In a device of the class described, the combination of a rectangular casing having an inclosed light chamber therein, a handle pivotally attached to said casing, a removable battery disposed within said casing, a cover with downward projecting edges for inclosing said casing, upper and rear reflectors in the light chamber, an opening in the forward wall of the light chamber having grooved way for receiving and retaining a plate of glass, an electric light bulb within said chamber mounted with one terminal in electric contact with the casing, the other terminal being connected to the central battery terminal by an L shaped bracket, a spring contact shoe mounted on the casing adjacent the other battery terminal and disposed within the path of the handle, all substantially as shown and described.

In witness whereof, I have hereunto affixed my signature in the presence of two witnesses.

LEIGH D. BRAINERD.

Witnesses:

M. J. PADDON,
CHESTER W. BROWN.
